UNITED STATES PATENT OFFICE.

JAMES F. BLANCHARD, OF GRAND ISLAND, NEBRASKA.

DESIGN FOR A MINERAL, STEAM, AND VIOLET-RAY, BATH-CABINET.

52,426.

Specification for Design.

Patented Sept. 17, 1918.

Application filed June 21, 1918. Serial No. 241,447. Term of patent 14 years.

To all whom it may concern:

Be it known that I, JAMES F. BLANCHARD, a citizen of the United States, and a resident of Grand Island, in the county of Hall and State of Nebraska, have invented a new, original, and ornamental Design for Mineral, Steam, and Violet-Ray, Bath-Cabinets, of which the following is a specification, ref-

erence being had to the accompanying drawing, forming a part hereof.

The figure is a perspective view of a cabinet showing my new design.

I claim:

The ornamental design for a mineral, steam, and violet ray, bath cabinet, as shown.

JAMES F. BLANCHARD.
